UNITED STATES PATENT OFFICE

125,868

DESIGN FOR A KNITTING PIN

Edward D. Davis, Chicago, Ill., assignor to The Boye Needle Company, Chicago, Ill., a corporation of Illinois

Application July 31, 1940, Serial No. 94,067

Term of patent 14 years

To all whom it may concern:

Be it known that I, Edward D. Davis, a citizen of the United States, residing at Chicago, county of Cook, and State of Illinois, have invented a new, original, and ornamental Design for a Knitting Pin, of which the following is a specification, reference being had to the accompanying drawing, forming a part thereof, in which:

Figure 1 is a plan view of a knitting pin, showing my new design; Fig. 2, an enlarged end view of the head of the pin; and Fig. 3, an enlarged view partly in section on line 3—3 of the head portion of the pin as shown in Figure 1.

I claim:

The ornamental design for a knitting pin, as shown.

EDWARD D. DAVIS.
